WATCH ADAPTER

Edmund A. Coleman, New York, N. Y.

Application January 2, 1935, Serial No. 78

2 Claims. (Cl. 63—2)

This invention relates to the manufacture of watches and more particularly to the provision of devices for the adaptation of wrist watches of standard type for use as pocket or pendant 5 watches in an extremely simple manner and with the production of a duplex article of pleasing and ornamental appearance.

A watch adapted for use as a wrist watch and as a pendant watch has heretofore been suggested but the production of such a watch requires a special casing with which special coupling devices must be used. Such a structure is interesting as a novelty but lacks commercial practicability for the reason that the special interacting members required in order to accomplish the desired interchangeability increase the cost of the article out of all proportion to the demand for it. Moreover, it is difficult to design a watch casing and special complementary coupling 10 members in such a fashion that the alternative use of the assembly will not be apparent to the observer, and a watch so designed, either when used as a wrist watch or as a pendant watch, leaves telltale indications that it is in fact only 15 temporarily fitted for that purpose. In other words, the fittings or connections necessary for one use are at least in part observable when the watch is being put to the alternative use, thereby detracting from the appearance and appeal of 20 the combination.

I have discovered that it is possible to provide a coupling member and a complementary ornamental member for use with the standard wrist watch without the provision of a special casing, so 25 that the wrist watch is changed in appearance only when the accessory members are attached thereto to change it into an attractive watch for pocket or pendant use. The coupling members are ornamental in nature and are shaped to fill 30 in the irregular outline of the watch case and to impart thereto a substantially regular contour having an attractive and finished appearance. The ornamental members are of sufficient bulk to render the assembly suitable for use as a pocket 35 watch.

These accessory members may be provided in such designs and finishes as will enable them to be attached to and used with the type and design of ordinary wrist watches, thereby effectively 40 adapting them for either use. The accessory members of the invention are simple in construction and may be very easily attached to and detached from the wrist watch in order to enable it to serve these dual functions.

55 The objects and advantages of the invention

will be readily perceived upon reference to the following specification and drawing, in which Fig. 1 is a perspective view of a standard type of wrist watch adapted for use with the invention; Figs. 2a and 2b illustrate in perspective the complementary accessory members which will adapt such watch for different purposes; Fig. 3 is a rear view of the watch of Fig. 1 with the accessory members attached thereto; Fig. 4 is a front view of the watch similarly assembled; Fig. 5 is a front view of a different type of standard wrist watch with modified novel complementary and ornamental members of the present invention attached; Fig. 6 is a rear view of the device of Fig. 5; and Fig. 7 is a detail in perspective with adjacent parts in 5 section, of one of the gudgeons with which I secure a strong and sturdy connection between the auxiliary members and the wrist watch frame.

In Fig. 1 the watch case 10 is provided with outwardly extending lugs or tabs 12, 13, 22 and 23, each provided with an opening 11 in which the ends of pintles 14 and 24 are adapted to be inserted. This is a wrist watch of the standard type now in use, the pintles 14 being constructed so that they yield or telescope against a spring in order to facilitate their insertion and removal in the openings 11 which serve as their bearings. Around each pinte the ordinary wrist watch strap is passed and when the strap is in place the assembly presents a neat and attractive appearance 10 which shows very little of the structure connecting the strap with the watch.

To replace the strap passing around the pinte, I provide complementary members 15 and 25 shown in Figs. 2a and 2b, 3 and 4. Member 15 is 15 made preferably of a flat piece of metal having its sides turned up as at 17 in order to give the member an appropriate depth, although the member may be constructed of heavy metal entirely. At the top is provided an eyelet 16 and 20 a ring to which a chain or ribbon is adapted to be connected. Along the lower edge of member 15 are provided slots 18 adapted to register with the tabs 12 and 13 on the watch case. Member 25 is similarly constructed with overturned portion 27 and slots 28 for the reception of lugs 22 and 23. Each member may be provided with a cut-out portion (not shown) at 26 in order to facilitate the insertion and removal of the corresponding pintles.

Integrally secured adjacent the lower edge of member 15 and the upper edge of member 25 are gudgeons 19 shaped as indicated in perspective in Fig. 7 and having an outwardly extending lip 21 50 55

adapted to extend over and contact against the side of the watch casing. Through the opening 20 in each of these members are inserted the pintles 14 and 24 and these pintles are compressed against 5 their internal springs sufficiently to shorten them longitudinally and allow their ends to be brought in line with the openings in the lugs 12, 13, 22 and 23, at which time they are released and the ends of the pintles allowed to seat themselves in 10 the openings in the lugs. This pinte and lug construction is, as I have previously indicated, well known in the art. The gudgeons or holding members fix the auxiliary members 15, 25, etc., in 15 position and lips 21 prevent them from turning about their pivots.

When the structure has been assembled, the result is similar to that shown in Fig. 4 with coupling member 15 and pendant member 25 securely attached to the watch and completely transforming it into a neat and attractive pocket or pendant watch, the alternative function of which is observable only to the eye of an expert.

In Figs. 5 and 6 I have shown front and rear views of another type of watch 31 in which the 25 sides of the watch case 30 are extended to form the lugs 32, 33, 42 and 43 in which appropriate openings are provided for the insertion of pintles 34 and 44. These pintles are similar to those 30 previously described and are removed from and inserted into the gudgeons 19 which are rigidly attached to the auxiliary members, and then snapped in place in the appropriate openings provided in the extending ends of the case. The result shown in Fig. 5 shows modified complementary members 35 and 45, the former being provided 35 with an eyelet 33. Fig. 6 shows the rear of such an assembly, the complementary members being shown as constructed with flanged sides 37 similar to 37 in Figs. 1-3. Such construction is illustrative merely of the manner in which an attractive

assembly is formed which gives little indication of the identity of the original watch.

It is apparent that when the watch is used as a wrist watch the standard wrist watch assembly is used, and there is no change in its structural features to mar its appearance. By a simple manipulation the strap or band of the wrist watch may be removed and the auxiliary members of the present invention substituted by attaching them to the standard strap fittings of the watch; 10 which is thus changed into a pocket or pendant watch of artistic appeal, giving little indication of its real identity.

Having thus described my invention, what I 15 claim is:

1. In combination with a wrist watch having longitudinally yielding pintles journaled in bearings provided at the sides of the watch case, a coupling member having a gudgeon integrally secured therewith, said gudgeon being disposed about one of said pintles and having a lip extending outwardly and parallel to the adjacent side of the case and thereby firmly positioning the coupling member with respect to the case, and a pendant member similarly attached to the opposite side of the case, said coupling member and pendant thus transforming said watch from a 20 wrist type into a pocket type.

2. In combination with a wrist watch having longitudinally yielding pintles journaled in bearings provided at the sides of the watch case, a pair of auxiliary members integrally secured to gudgeons disposed about said pintles, each of said gudgeons having an outwardly extending lip parallel to and substantially contacting the adjacent side of the case, said auxiliary members being thereby substantially fixedly positioned on said case and transforming the watch into a pocket 25 type watch.

EDMUND A. COLEMAN.
